UNITED STATES PATENT OFFICE.

HENRY B. WINTERS AND JOHN E. McCORMICK, OF ELKHART, KANSAS; SAID WINTERS
ASSIGNOR TO SAID McCORMICK.

WELL-CASING COUPLING.

Application filed December 17, 1920. Serial No. 431,400.

To all whom it may concern:

Be it known that we, HENRY B. WINTERS and JOHN E. McCORMICK, citizens of the United States, residing at Elkhart, in the 5 county of Morton and State of Kansas, have invented certain new and useful Improvements in Well-Casing Couplings, of which the following is a specification.

This invention relates to an improved 10 well casing coupling and has as one of its principal objects to provide a coupling wherein the sections of a well casing may be quickly and securely connected.

A further object of the invention is to 15 provide a coupling employing a plurality of coupling straps which may be easily applied for securing the casing sections together.

And the invention has as a still further 20 object to provide a coupling employing retaining means for the free ends of the straps so that the straps will not pull out under pulling stress upon the casing.

Other and incidental objects will appear hereinafter.

25 In the drawings:

Figure 1 is a fragmentary perspective view showing a coupling embodying the present invention,

Figure 2 is a transverse sectional view 30 looking downwardly upon the coupling, and

Figure 3 is a fragmentary vertical sectional view on the line 3—3 of Figure 2.

In carrying the invention into effect, we 35 employ casing sections 10 and 11 respectively which are formed at their meeting ends to telescope one within the other, the section 11 being limited in its movement over the section 10 by an annular stop shoulder 12. Snugly surrounding the section 10 above said shoulder is a collar 13 riveted or 40 otherwise secured at spaced points to the section and formed from said collar is a plurality of outwardly or radially directed stirrups 14. Preferably, the collar is provided with three of said stirrups and, as 45 will be observed upon reference to Figure 2 of the drawings, the rivets securing said collar are arranged substantially midway between the stirrups. Formed through the 50 lower end portions of said stirrups near the lower edge of the collar are slots 15 below which are defined keepers 16. Snugly

surrounding the casing section 11 near its adjacent end is a collar 17. This collar is a counterpart of the collar 13, being similarly secured and provided with a plurality of stirrups 18. These stirrups correspond to the stirrups 14 and are provided near their upper ends adjacent the upper edge of the collar with slots 19 above which are defined keepers 20. As shown in Figure 1, the casing sections are fitted together in such manner that the stirrups 14 and 18 are aligned and fitting through said stirrups are coupling straps 21. These straps are 60 each preferably formed from a length of suitable resilient sheet metal and, as will be noted, the upper end portions of the straps are looped over the stirrups 14 and inserted through the slots 15 to engage beneath the 65 keepers 16 while the lower end portions of the straps are looped over the stirrups 18 and inserted through the slots 19 to engage beneath the keepers 20. The straps will thus rigidly connect the casing sections 70 while the keepers will retain or tie the free end portions of said straps so that the straps will not pull out under pulling stress upon the casing. We accordingly provide a coupling of highly effective construction and a 75 coupling which may be readily employed in connection with well casings now commonly in use.

Having thus described the invention, what is claimed as new is:

The combination with casing sections telescopically connected, one of said sections having an annular shoulder abutting against the adjacent edge of the other of said sections; of collars secured on the sections at the adjacent ends thereof, radial stirrups integral with said collars extending between the edges thereof, keepers on the stirrups formed on a longer radius than the stirrups, and coupling straps passing 90 under the stirrups and having their free end portions bent back over the remote edges of the stirrups and engaged through the keepers.

In testimony whereof we affix our signatures.

HENRY B. WINTERS. [L.S.]
JOHN E. McCORMICK. [L.S.]
